BY Victor J. Evans

ATTORNEY

WITNESS:

UNITED STATES PATENT OFFICE.

LE ROY GARRY CURTIS, OF EVERETT, WASHINGTON.

LOCK.

Application filed December 14, 1923. Serial No. 680,695.

To all whom it may concern:

Be it known that I, LE ROY GARRY CURTIS, a citizen of the United States, residing at Everett, in the county of Snohomish and 5 State of Washington, have invented new and useful Improvements in Locks, of which the following is a specification.

My present invention has reference to a door lock.

10 In carrying out my invention it is my purpose to produce a door lock with a cylindrical casing so that the same may be inserted in a round opening bored in a door and the tedious and laborious practice of 15 mortising the door for the reception of the lock casing, overcome.

A further object is to produce a door lock that includes a spring influenced bolt normally operated by the spindle to which the 20 knobs are secured and being also provided with means for locking the same against movement, as when the door is to be held closed.

The foregoing and other objects which 25 will present themselves as the nature of the invention is better understood, may be accomplished by a construction, combination and operative association of parts such as is disclosed by the drawings which accompany 30 and which form part of this application.

In the drawings:—

Figure 1 is a side elevation of a door and jamb therefor illustrating the application of the lock, a portion of the door and jamb 35 being in section.

Figure 2 is an edge view of the door looking toward the lock.

Figure 3 is a sectional view on the line 3—3 of Figure 1.

40 Figure 4 is a sectional view on the line 4—4 of Figure 3.

Figure 5 is a perspective view of the lock-ing bolt.

Figure 6 is a view of the tumblers which 45 provide the locking means for holding the bolt against movement.

Figure 7 is a perspective view of the tumblers in assembled relation.

Figures 8 and 9 illustrate details.

50 As disclosed by the drawings, my lock can be attached to a door 1 by simply boring a hole through one edge thereof, and also boring a hole transversely with respect to the first mentioned hole. The lock casing comprises a cylindrical member 1, the same, however, having its outer end provided with

a face plate 2 which is preferably let in a depression in the edge of the door. The cylindrical casing 1, of course, is received in the longitudinal opening bored in the door, 60 and in the transverse opening there is arranged a cross sectionally rounded sleeve 3 having a squared bore through which passes a square spindle 4 that has on its ends the knobs 5. The knobs contact with escutcheon 65 plates 6 which are screwed in the sides of the door. The escutcheon plates are preferably T-shaped, their shorter and central branches being provided with key-hole openings 7 which register with key-hole openings 8 in the sides of the tubular lock casing 1.

Arranged for slidable movement through the tubular casing 1 there is a bolt member. The bolt member is round in cross section and includes a solid outer portion 9 and an 75 inner tubular portion 10. The solid portion 9 has one of its faces beveled as at 9', whereby the same may be retracted against the spring of the bolt (hereinafter described) when the bolt passes over the keeper 12 in 80 the jamb 13. The inner end of the solid portion 9 of the bolt is reduced, as at 50, so that the tubular portion 10 fits thereover, a removable pin 14 passes through a slot 51 in the reduced portion 50 and the tubular portion 10 holding the parts 9 and 10 together. It will be apparent that the angle or beveled 85 edge of the bolt may be arranged upon either side of the lock casing so that the door can swing through either side of the jamb. 90

The tubular casing 1 has its sides, from its inner end provided with aligning longitudinal slots 15. The sleeve 3 is provided with an eye 16. Through this eye 16 there passes the rounded central portion of a bail-like member 17. The member 17 is formed of a strand of wire and the arms thereof are bent at opposite outward angles at the ends thereof, the said angle ends indicated by the numeral 18, passing through openings 19 in the ends of the tubular section 10 of the bolt and being also received in the slots or notches 15 in the lock casing 1. Surrounding the parallel arms of the bail-shaped member, in contact with the angle end portions 18 thereof, and also in contact with a pin 20 that passes transversely through the lock casing 1, there is a helical spring 21. The spring, of course, influences the bolt to projected, and therefore to locking position, but it will 100 be apparent that when the spindle is turned by the knobs 5 the bail-shaped member will 105 110

swing upon its pivotal connection with the locking bolt and be guided through the slots 15 in the casing 1, retracting the bolt. A release of either of the knobs will permit the 5 springs to return the bolt to initial locking position.

It is, of course, desirable that the bolt be sustained in locking position, so that the door to which the device is attached cannot 10 be opened by unauthorized persons, and to provide for this I produce a simple but thoroughly effective locking means. The locking means includes a pair of members which I shall refer to as tumblers and which 15 are designated in the drawings by the numerals 21 and 22 respectively. The member 21 is what I will term the slidable element of the locking device, the element 22 being in the nature of the swingable element 20 of the locking device. The element 21 is in the nature of a rectangular plate, being provided with an elongated opening 23 through which passes a pivot 24 that is secured to the sides of the hollow member 10 of the bolt. 25 To properly guide the member 21 in its sliding movement in the bolt, I form one corner thereof with an extension 25 which is in contact with the wall of the bolt opposite that engaged by the opposite edge of the 30 member 21. The member 21, on its edge and adjacent its corner opposite that provided with the extension 25 has a transverse notch 26 therethrough and an outwardly and downwardly inclined passage 27 that 35 communicates with the notch. The member 22 is substantially hook-shaped, that is one end thereof is provided with an angle extension in the nature of a beak 28, the body of the member being provided with a round opening 29 through which the pivot member 40 24 passes. The end of the member 22, opposite that provided with the beak 28 is widened and is formed with a V-shaped notch 30. The member 22 is provided on 45 one of its sides with a projecting pin or lug 31 that is designed to be received in the notch 26 and in the passage 27 when the device is in locking position and when the beak 28 passes through registering openings 50 32 and 33 in the bolt and in the casing 1. The stud 31 normally rests on the upper edge of the member 21, being sustained thereon through the medium of a spring 34 which is secured to the pivot 24 and to the 55 member 22. The spring 34 causes the member 21 to move toward the inner end of the bolt and casing, such movement causing the stud 31 to ride on the angle wall of the passage 27 upwardly and, as previously 60 stated, on to the upper edge of the said member 34. To bring the elements to locking position, a key having a suitable bit is inserted through the key-hole openings 7 and 8, the bit is first brought against the 65 straight inner edge of the slidable member

34, moving the same so that the stud 31 will be brought in alignment with the notch 26, a further turning of the key engaging what I will term the upper angle wall provided at the V-shaped notched end 30 of the member 22, swinging the said member 22 to bring the bit 28 thereof into the aligning notches 32 and 33 of the bolt and of the casing. As the key moves off of the wall of the member 22, the spring 34 will exert its influence to 70 return the member 21 to initial position, thus causing the angle wall of the passage 27 to ride more effectively over the stud 31 and more effectively bring the bit 28 into the notches or openings 32 and 33. A movement of the key in a reverse direction will 75 reverse the action above described, permitting the unlocking of the bolt from the casing 1 and the free sliding of the bolt on the turning of the knobs 3.

Having described the invention, I claim:

1. A lock having a cylindrical casing which is slotted, a bolt slidable in the casing, a bail having angle ends connected to the bolt and entering the slots of the casing, a revoluble element connected to the bail, and spring means surrounding the bail contacting the casing and the angle arms of the bail.

2. A lock including a cylindrical casing which is slotted longitudinally, a bolt having a hollow inner end slidable through the casing, a bail having angle ends passing through the bolt and entering the slots of the casing, a pin in the casing passing between the arms of the bail, a revoluble element loosely connected with the bail, a spring surrounding the arms of the bail contacting the ends thereof and the pin whereby to hold the bolt normally in latching position.

3. A lock including a cylindrical casing which is slotted longitudinally, a bolt having a hollow inner end slidable through the casing, a bail having angle ends passing through the bolt and entering the slots of the casing, a pin in the casing passing between the arms of the bail, a revoluble element loosely connected with the bail, a spring surrounding the arms of the bail contacting the ends thereof and the pin whereby to hold the bolt normally in latching position, and means in the bolt for engaging the casing for locking the bolt in latching position.

4. A lock including a cylindrical casing which is slotted longitudinally and which is provided with a notch, a cross sectionally rounded bolt including a hollow inner section arranged for slidable movement in the casing, a bail having angle ends passing through the bolt and received in the slots of the casing, a pin in the casing received between the arms of the bail, a spring surrounding the bail exerting a tension between the pin and the ends of the bail, a revoluble element loosely connected with the bail for

moving the bolt to unlatching position, a pivoted and a slideable tumbler in the bolt, said pivoted tumbler having an offset designed to be received through an opening in the bolt and to enter the notch in the casing and being further provided with an offset stud, said slideable tumbler having a notch and an angle passage communicating therewith to receive the stud therein when the 10 finger of the stud is in latching position, and spring means influencing the slideable tumbler to cause the latter to move to retain the stud in the angle passage of the notch or to sustain the lug of the swinging tumbler over the movable tumbler when the first 15 mentioned tumbler has been swung and the last mentioned tumbler has been moved.

In testimony whereof I affix my signature.

LE ROY GARRY CURTIS.
